UNITED STATES PATENT OFFICE.

JOSEPH V. DESMARAIS, OF NEW BEDFORD, MASSACHUSETTS.

STOP-MOTION FOR JACQUARD LOOMS.

1,198,706.

Specification of Letters Patent. Patented Sept. 19, 1916.

Application filed July 19, 1915. Serial No. 40,763.

To all whom it may concern:

Be it known that I, JOSEPH V. DESMARAIS, a citizen of the United States, and resident of New Bedford, county of Bristol, State of 5 Massachusetts, have invented certain new and useful Improvements in Stop-Motions for Jacquard Looms, of which the following is a specification.

My invention relates to stop mechanisms 10 for looms, particularly looms using drop box mechanisms for weaving in colors and which employ jacquard or dobby heads.

It sometimes happens in the operation of 15 looms which use jacquard or dobby heads to weave patterns in the cloth and which also use a drop box color mechanism to vary the color of the woof threads, that the two mechanisms do not properly act together. Thus the pattern or chain controlling the 20 drop box color mechanism may be ahead or behind the corresponding jacquard cards or dobby chains of cards.

When the loom is working correctly each 25 card in the head of the machine comes into operative position simultaneously with a card or portion of a chain which will cause the drop box color mechanism to so operate that the woof thread of proper color is thrown through the shed. If the head patterns for 30 any reason do not coöperate with the color mechanism, as when one set of patterns is ahead or behind the other, the wrong color may be woven into the cloth and unless the defective weave is immediately noticed by 35 the attendant and the loom stopped and the cards properly rearranged, the loom will continue to operate in this way to the detriment of the product.

The object of my invention is to provide a 40 simple, inexpensive, and efficient means for stopping the loom when, for any reason, the apparatus for selecting the woof thread does not select the proper color.

Another object is to prevent the loom 45 from being started on wrong pick. When my invention is applied to a loom it is impossible for an attendant to start it unless the head cards are in proper relation to the box cards or chains.

50 Other objects and uses will be apparent as the invention is more fully described.

Referring to the drawings, Figure 1 is a 55 diagrammatic representation of a loom with jacquard head and color box chains, and showing the essential features of one form of my stopping device; Fig. 2 is a representa-

tion of a jacquard cylinder and cards showing a detail of one form of my loom stopping device; Fig. 3 is a side elevation of a portion of a dobby head showing the manner in which the stopping device is applied thereto; Fig. 4 is a perspective view of the frame of a loom with part of my special stopping device mounted on the side thereof instead of underneath, as in Fig. 1; Fig. 5 60 is an end elevation of part of a loom showing one form of my invention in which the shuttle boxes are connected to the stop mechanism; Fig. 6 is a view of the special jacquard needle used in one form of my stop 65 mechanism.

In the drawings the various parts are represented by different numerals and each numeral represents the same part of the mechanism in the different views.

Referring to Fig. 1, the frame 10 of the 70 loom is of usual construction and carries the usual stopping shaft 11 which may be manually actuated by one or more levers 12, and on this shaft I secure an arm 13.

My invention provides for automatically 75 actuating the shaft 12 and stopping the loom when the loom mechanism picks the wrong shuttle or color. The bracket 14 is arranged on the frame 10 and has pivoted 80 thereto by means of the bolt 14' two bell crank levers 15 and 16. A wire, cord or link 17 connects one arm of lever 16 to the end of the arm 13 so that when the lever 16 is rocked on its pivot, to the right (Fig. 1) the 85 shaft 11 will be actuated to stop the loom. On the other arm of lever 16 is pivoted a smaller lever or dog 18 from which a tooth 19 projects downwardly. Levers 15 and 18 are in the same plane and when the lever 18 90 is depressed slightly the tooth 19 can be engaged by the end of bell crank lever 15 if the latter is swung on its pivot. The lever 18 is normally depressed by gravity so that the tooth 19 is in the path of one end of 95 bell crank lever 15. To the end of dog 18 is attached a wire or cord 20 which passes over pulleys 21 and 22 and is attached to one end of a lever 23 having a fixed fulcrum at 24 adjacent the box chain cylinder. The 100 weight of both of the levers 18 and 23 tends to hold the lever 23 against the box chain 25 which controls the operation of the color boxes in the usual manner.

110 Projections or lugs 26 are provided on the chain 25 and adapted to engage the lever 23 to raise the same as the chain passes

around the cylinder 27. Whenever the lever 23 is raised in this manner the cord or wire 20 is pulled and lever 18 is lifted so that the tooth 19 is out of the path of end of lever 15.

5 The lever 15 is weighted so as to have a normal tendency to turn to the left (Fig. 1) on the pivot 14'. To the left end of the lever 15 is attached a cord or wire 28 having its upper end connected to one of a 10 pair of jacquard hooks 29 and 30. These hooks may be the special hooks on the outside of the head, which are provided in some looms to operate the box chains and are controlled by a needle 31 of the usual 15 type which coöperates with the pattern cards 32. Instead of actuating the hooks 29 and 30 by means of the needle 31, a special needle 33 may be provided which also engages the hooks 29 and 30 and controls 20 them in their coaction with the griffs 34.

The special needle 33 is not within the regular jacquard head but is outside and can only engage the hooks 29 and 30 because of a deep bend 33' in the needle. The needle 25 33 may be actuated in the same manner as the regular jacquard needles and may coöperate with special holes cut in the ends of the pattern cards but preferably this needle coöperates with special holes 32'.

30 When the special needle 33 enters the hole 32' in the face of the cylinder 35, the hooks 29 and 30 are thrown forward and are raised by the griff blades 34 in the usual manner. The cord or wire 28 is thereby 35 drawn upward and the lever 15 rocked on its pivot 14'. If lever 23 has been raised at the same instant by one of the lugs 26 on the box chain 25, so as to lift the dog 18, the end of the lever 15 will miss the tooth 19 40 and the lever 16 will not be actuated. If, for any reason, a lug 26 on the box chain does not arrive in position to raise the lever 23 and dog 18 simultaneously with the actuation of the lever 15 the end of lever 15 will 45 engage tooth 19 of dog 18 and cause lever 16 to be actuated, thereby pulling down arm 13 and actuating shaft 11 to stop the loom.

The jacquard cylinder 35 may have a hole 50 in only one face or a hole in each of two opposite faces and the spacing of the lugs 26 on the box chain corresponds with the arrangement of the special holes in the cylinder.

55 It will be apparent from the foregoing that the loom will be stopped as soon as the cylinder 35 gets out of proper step with the box chain 25. The loom cannot be started on the wrong pick of color such as 60 would occur if the attendant has not set the pattern cards and the box chain in proper relation and, even if the loom is properly set and started, but, for any reason, the cylinder 35 gets out of time with the 65 box chain, it is immediately stopped.

In Fig. 2 is shown a modification of the head in which no special needle is used and there is no need of a special hole in the jacquard cylinder. In this form the two hooks 29^a and 30^a are controlled by an ordinary jacquard needle 36, which is intended to enter a special hole 36' cut in every second, fourth, sixth or eighth, card. The stop mechanism is otherwise the same as in Fig. 1. This form of the invention may not be 70 as desirable as that shown in Fig. 1 for the reason that the cards must have the extra hole cut in them and also because the ends of the cards are sometimes used to work the indication of the loom.

Fig. 3 shows part of a common form of dobby head with a cord 37 attached to the harness lever 38. The lower end of cord 37 is attached to bell crank lever 15, as in the case shown in Fig. 1.

80 In Fig. 4 my stop mechanism is shown attached to the side of a loom instead of underneath. The lever 16^a is actuated by lever 15^a through dog 18^a to pull cord 17^a the same as in Fig. 1. A bell crank lever 39 mounted on a small bracket 40 secured to the side of the loom, will, when actuated by cord 17^a push shipper lever 41 out of the notch 42 into the slot 43. The shipper 41 is a type that is in common use on certain makes 90 of looms and when pushed out of notch 42 is thrown longitudinally of slot 43 to stop the loom.

When no box chains are used on a drop box loom the stopping device is arranged 100 as in Fig. 5. In this form the color boxes are mounted on vertical rods 45 pivoted at their lower ends to arms 46 of a rock shaft 47. The color boxes are moved up and down by the rocking of shaft 47. A cord 20^b 105 transmits this motion from the arm 46 to the dog 18^b. The box raising and lowering mechanism is so arranged that, on every second or fourth pick, the boxes are brought back to the lowest position so that the up- 110 permost shuttle is in position to be thrown. Only when the boxes are in this lowest position is the dog 18^b raised out of the path of lever 15^b. If the lever 15^b is actuated, by the head when the boxes are not in the lowest 115 position, it will engage dog 18^b and the bell crank lever 16^b will be rocked and the loom stopped.

Having described my invention what I claim and desire to secure by Letters-Pat- 120 ent is,

1. In a loom, the combination of means for stopping and starting the operation thereof, a plurality of shuttles, mechanism for automatically placing any desired shuttle 125 in position to be thrown, mechanism for selecting and lifting the warp threads, said mechanisms operating in synchronism to produce a given design, and means coacting with each of said mechanisms and connected 130

with said means, whereby the latter is actuated when the desired synchronism between said mechanisms is destroyed.

2. In a loom, the combination of means 5 for starting and stopping the operation thereof, a plurality of shuttles, mechanism for selecting the shuttle to be thrown, mechanism for selecting and lifting the warp threads, said mechanisms coöperating with 10 each other to produce a given design, a normally stationary lever connected to said means, a periodically moving lever actuated by the warp thread lifting mechanism, and a member operated by said shuttle selecting 15 mechanism and adapted to operatively connect said levers when the coöperative relationship between said mechanisms is destroyed.

3. In a loom, the combination of means 20 for starting and stopping the operation thereof, a plurality of shuttles, mechanism for selecting any shuttle desired to be thrown, mechanism for selecting and lifting the warp threads, said mechanisms coöperating with each other to produce a given design, a normally stationary lever operatively connected to said means, a periodically moving lever actuated by said warp lifting mechanism, a dog pivoted to said first-mentioned 25 lever normally in the path of said second mentioned lever, said dog being operatively connected to said shuttle selecting mechanism whereby the dog is normally moved out of the path of the second mentioned lever in 30 time with the actuation of the latter.

4. In a loom, the combination of means for starting and stopping the operation thereof, a plurality of shuttles, mechanism for automatically selecting the shuttle to be 40 thrown, mechanism for selecting and lifting the warp threads, said mechanisms coöperating with each other to produce a given design, a normally stationary lever operatively connected to the stopping mechanism, a periodically moving lever actuated by the warp lifting mechanism, a dog carried by one of said levers and normally in position to engage the other lever, said dog being operatively connected to said shuttle selecting 45 mechanism whereby the dog is periodically moved out of its normal position in timed relation to the movements of said periodically moving lever so as to normally avoid actuating said stationary lever.

5. In a loom, the combination of means 55 for starting and stopping the operation

thereof, a plurality of shuttles, mechanism for automatically selecting the shuttle to be thrown, mechanism for selecting and lifting the warp threads, said mechanisms coöperating with each other to produce a given design, and means comprising a lever connected to said stopping means, a lever movable relatively thereto and operatively connected to said selecting and lifting mechanism, and a member operated by said shuttle selecting mechanism, whereby said second mentioned lever is operatively connected to said first mentioned lever to move the same to actuate said stopping means, when the coöperative relationship between said mechanisms is destroyed. 60 70

6. In a loom, the combination of means for starting and stopping the operation thereof, a plurality of shuttles, mechanism 75 for automatically selecting the shuttle to be thrown, jacquard mechanism for selecting and lifting the warp threads, said mechanisms coöperating with each other to produce a given design, a normally stationary 80 member operatively connected with said means, means periodically actuated by said jacquard mechanism, a member adapted to form a connection between the last mentioned means and the first mentioned member, and means whereby the last mentioned member is periodically operated in timed relation to the last mentioned means to normally prevent the actuation of the first mentioned member thereby. 90

7. In a loom, the combination of means for starting and stopping the operation thereof, a plurality of shuttles, mechanism for automatically selecting the shuttle to be thrown, jacquard mechanism, a member operatively connected with said means, a special needle in said jacquard mechanism, periodically actuated means controlled by said special needle and adapted to be operatively connected with said member to 95 100 actuate the first mentioned means and means periodically actuated by the first mentioned mechanism in timed relation to the actuation of said last mentioned means, means whereby the actuation of said member is 105 normally prevented.

In testimony whereof I affix my signature.

JOSEPH V. DESMARAIS.
